OPTICAL INSPECTION APPARATUS FOR USE
IN INSPECTING POTENTIOMETER CARDSJohn S. Stull, Chicago, Ill., assignor to Western
Electric Company, Incorporated, New York,
N. Y., a corporation of New York

Application June 6, 1945, Serial No. 597,768

6 Claims. (Cl. 88—14)

1

This invention relates to inspection apparatus and more particularly to apparatus for use in inspecting potentiometer cards.

An object of this invention is to provide an apparatus by means of which potentiometer cards may be conveniently and efficiently inspected.

In one embodiment of the invention, there is provided an arcuate carrier, pivotally mounted for guiding a potentiometer card carried thereby in a predetermined path to guide successive portions thereof under a microscope where the card may be inspected, the card being moved by actuation of the carrier through the manual rotation of a capstan drivingly connected to the carrier by a strand.

The invention will be more fully understood from the following description taken in connection with the attached drawings, in which

Fig. 1 is a plan view of the apparatus with parts shown in section;

Fig. 2 is a detailed sectional view taken on the line 2—2 of Fig. 1;

Fig. 3 is a vertical cross sectional view taken along the line 3—3 of Fig. 1 with parts broken away;

Fig. 4 is an enlarged front elevational view of a portion of the device showing a potentiometer card mounted on the apparatus;

Fig. 5 is a fragmentary vertical sectional view taken along the line 5—5 of Fig. 4;

Fig. 6 is an enlarged fragmentary plan view of the potentiometer card, and

Fig. 7 is an enlarged fragmentary sectional view of the capstan.

The inspection apparatus is used for inspecting potentiometer cards 10 or other elongated articles. The potentiometer cards vary in size and shape and consist of an elongated flat form or card 11 of dielectric material and predetermined outline having a straight top edge and upon which a fine wire 12 is closely wound. The convolutions of the wire 12 are spaced apart from each other and the insulating coating surrounding the wire is removed from a portion of the wire at the top edge of the potentiometer card to bare the metallic wire and form a contacting surface for engagement with the usual cooperating contact member, and it is this part of the potentiometer card that is inspected.

The inspection apparatus comprises a frame or carrier 15 in the shape of a quadrant having an arc-shaped rim 17 and converging ribs 18 meeting to form an elongated vertical hub 19. The carrier is mounted for pivotal movement on a shaft or pin 20 which passes through an aperture 21 in

2

the hub 19 and which is secured in apertures 23 and 24, respectively, of a base member 25 and a bracket 26 mounted on the base. A pair of anti-friction bearings 28 and 29 are provided in the hub 19 and cooperate with members 30 and 31, respectively, to rotatably support the carrier on the shaft 20. A lock nut 32 engaging the upper threaded portion of the shaft 20 cooperates with the member 30 also threadedly engaging the shaft 20 to maintain the member 30 in position. To retard the rotation of the carrier 15, a pair of brake members 35 and 36, slidably mounted in the bracket 26, are urged against the outer cylindrical surface of the hub 19 by a leaf spring 37 carried by the bracket 26. The rim 17 of the carrier is raised to form a card supporting surface 40, against which the potentiometer card is clamped by a plurality of clamps 41 spaced apart and carried on the rim 17. Each of the clamps 41 comprises a movable jaw member 42 apertured at 43 to loosely pass over and pivot on a pin 44 carried by the rim 17 and a U-shaped bracket 45. The U-shaped brackets 45 are secured to the rim 17 of the carrier and are apertured at 46 to rotatably support thumb screws or threaded members 47 which engage the threaded apertures 48 in the jaws 42. The members 47 may be turned to rock the members 42 about the pins 44 and thereby move the upper ends of the jaws 42 open against the action of bowed leaf springs 49 interposed between the jaws 42 and the arms of the U-shaped brackets 45. Upon movement of the member 47 in the opposite direction to a point where the head of the member 47 is disengaged from the U-shaped brackets, the jaw 42 will be closed by the action of the spring 49 which will apply a uniform pressure thereto to clamp the card against the surface 40 of the rim 17.

To accurately position the potentiometer card so that its top edge is in a horizontal plane, a gage in the form of a flat member 51, having an arcuate edge, is mounted on the carrier 15. The gage 51 is provided with parallel slots 55, through which pass securing studs 56. The gage member 51 is adapted to be moved forward to overlie and project beyond the rim 17 in which position the potentiometer card may be moved upward into engagement therewith while the potentiometer card is being applied to the carrier 15 and clamped in place by clamping members 41. After the potentiometer card has been clamped in place, the gage member 51 may be moved back to the position shown in Figs. 1 and 3 in which position the top edge of the potentiometer card, which is

to be inspected, is exposed and in view of the operator.

An optical device in the form of a microscope 60, through which the potentiometer cards are inspected, is mounted on the base 25 in a position adjacent the rim 17 of the carrier. The microscope 60 is adjustable vertically in alignment with a portion of the potentiometer card, as indicated in Fig. 3, a control handle 61 mounted in the base 62 being provided for effecting the adjustment.

To actuate the carrier and move the card under the microscope, actuating mechanism is provided which includes a capstan 63 and a cord or strand 66 operatively connecting the capstan to the carrier. The capstan 63 is rotatably secured to the base 25 by a cap screw 64 and is provided with a knurled flange or handle portion 65. Intermediate its ends, the cord 66 is wrapped around the capstan 63 and is attached at one end to an arm 67 secured to the carrier, and at the other end to an arm 68 pivotally mounted at 10 to the carrier 15. The arm 68 is fixed to a pin 71 which extends through an aperture 72 in the upper end of a boss 73 formed in one of the ribs 18. The pin 71 is retained on the carrier by a collar 74 and has an enlarged shoulder 76 formed thereon engaging the lower portion of a cylindrical recess 77 formed in the boss 73. A spring 80, surrounding the pin 71 and having its ends 81 and 82 fixed to the boss 73 and the arm 68, respectively, is provided to exert force tending to turn the arm 68 in a counterclockwise direction, as viewed in Fig. 1. The cord 66, fastened at one end to the arm 68, is thus maintained taut and thereby eliminates any lost motion in the connection between the capstan and the carrier 15. The arm 68 is angular in shape and extends out from one side of the carrier to permit the carrier to be moved to one side of the capstan 63.

The apparatus, when applying a potentiometer card thereto, is positioned to the left side of the microscope in which position the rim 17 and the clamping members are accessible to the operator. The threaded members 41 of the clamping devices 42 are turned to open the clamping jaws 42, after which a potentiometer card is inserted between the jaws 42 and the rim 17. With the potentiometer card loosely positioned between the jaws and the rim 17, the gage member 51 is moved forward into a position to overlie the potentiometer card, as indicated in dotted lines in Fig. 5. The potentiometer card may then be moved upwardly to engage the underneath surface of the gage 51 to vertically position the card on the carrier after which the threaded members 41 may be turned to permit the closing of the jaws by the springs 49. The gage 51 may then be moved back to expose the top edge of the potentiometer card and the apparatus is then in condition to be actuated to move the card under the microscope. This is accomplished by manually turning the capstan 63 which imparts movement through the cord 66 to the carrier 15 and the potentiometer card 10. The operator may then inspect the wires of the potentiometer card through the microscope 60 and turn the capstan as required to move successive portions of the card into the field of the microscope until the card has been completely inspected. When not used to move the carrier and the potentiometer card thereon, the capstan 63 and the taut cord 66 act to hold the potentiometer card still to facilitate its inspection. By employing a capstan of relatively small diameter, the movement of the carrier and the

potentiometer card may be accurately and minutely controlled. It will be noted that the potentiometer card is held in its curved position on the carrier by the individual clamps which exert a limited predetermined pressure against the cards. Cards of various lengths may be inspected on this device and cards of a length in excess of the length of the rim 17 may be inspected in sections.

What is claimed is:

1. An inspection apparatus comprising a base, a movable member for supporting a potentiometer card thereon, means mounting said member on said base for movement in a predetermined path, a gage member on said card supporting member for positioning said card with the edge thereof in a predetermined position on said movable card supporting member and parallel to the path of movement of said card supporting member, holders for holding said card in position on said card supporting member, a stationary optical inspection device mounted on said base adjacent the path of movement of said card supporting member for use in inspecting said card, a strand having one end thereof attached to said card supporting member, yieldable means carried by said card supporting member for receiving the other end of said strand in spaced relation to said one end to maintain said strand in taut condition on said card supporting member, and a capstan encircled in operative engagement by the intermediate portion of said strand, said capstan being rotatable for moving said strand to effect a movement of said card supporting member in said predetermined path to move successive portions of the edge of said card into the field of said optical device.

2. An inspection apparatus comprising a base, a carrier member having an arcuate surface for supporting a potentiometer card in an arcuate position thereon, holders for holding said card in said arcuate position on the arcuate surface of said carrier, a pivot support for pivotally mounting said carrier on said base for turning movement about an axis concentric with said arcuate surface whereby said arcuate surface is guided in a predetermined path, a stationary optical inspection device mounted on said base adjacent said predetermined path for use in inspecting the card on the carrier member, a rotatable member mounted on said base, a cord having its intermediate portion encircling and operatively engaging said rotatable member, means for connecting the ends of said cord at widely separated points to said carrier, and resilient means associated with said cord for maintaining said cord taut and in operative engagement with said rotatable member, said rotatable member being actuatable to move said cord and said carrier and thereby move successive portions of said card into the view of said inspection device.

3. An inspection apparatus comprising a base, a carrier having an arcuate portion for supporting a potentiometer card in an arcuate position thereon, a plurality of clamping members mounted on said carrier for holding the potentiometer card in said arcuate position on said arcuate portion of said carrier, springs for moving said clamping members to closed position, means for moving said clamping members to open position, a pivot support for pivotally mounting said carrier on said base for turning movement about an axis concentric with said arcuate portion whereby said arcuate portion is guided in a predetermined path, a movable gage member

mounted on said carrier and engageable with the edge of said card for use in axially positioning said card in a predetermined position on the arcuate portion of said carrier and with its edge parallel to the predetermined path of movement of said carrier, a stationary optical inspection device mounted on said base adjacent said predetermined path for inspecting the card on said carrier, a capstan mounted on said base, a strand having its intermediate portion encircling and operatively engaging said capstan, means for connecting the ends of said strand at widely separated points to said carrier, and resilient means associated with said strand for maintaining said strand taut and in operative engagement with said capstan whereby, upon rotation of said capstan, the strand is moved to rotate the carrier about said axis, thereby to bring successive portions of the card mounted on said carrier into the field of said optical inspection device.

4. An inspection apparatus comprising a base, a carrier having an arcuate surface for supporting a potentiometer card in an arcuate position thereon, a plurality of holding members mounted on said carrier for holding said potentiometer card in said arcuate position on said carrier, a pivot support pivotally mounting said carrier on said base to turn about an axis concentric with said arcuate surface whereby said arcuate surface is guided through a predetermined path, a movable gage member mounted on said carrier and engageable with an edge of said card for use in axially positioning said card in a predetermined position on the arcuate surface of said carrier and with the edge of the card parallel to the predetermined path of movement of said carrier, an arm pivotally mounted on said carrier adjacent one edge thereof, an optical inspection device mounted on said base adjacent said predetermined path for inspecting the card on said carrier, a capstan mounted on said base, a strand having its intermediate portion encircling and operatively engaging said capstan and having one of its ends attached to said pivoted arm and its other end attached to said carrier adjacent another edge thereof spaced from and opposite said one edge, and spring means urging said arm for rotation in one direction to maintain said cord taut and in operative engagement with said capstan, said capstan being rotatable to move said strand and said carrier and thereby bring successive portions of the edge of the card mounted on the carrier into the field of the optical inspection device.

5. An inspection apparatus comprising a base, a carrier having an arcuate portion for supporting a potentiometer card in arcuate position thereon,

a plurality of clamping members mounted on said carrier for holding said potentiometer card in said arcuate position on said carrier, a pivot support for pivotally mounting said carrier on said base to turn about an axis concentric with said arcuate portion whereby said arcuate portion is guided through a predetermined path, an optical inspection device mounted on said base adjacent to said predetermined path for use in inspecting said card, a member movably mounted on said carrier, a strand connected at one end to said movable member and at its other end to said carrier at a point widely separated from said one end, a capstan mounted on said base and encircled in operative engagement by the intermediate portion of said strand, and spring means tending to move said movable member to maintain said strand taut and in operative engagement with said capstan whereby, upon rotation of said capstan, the strand is moved to advance the carrier and thereby move successive portions of the card mounted on the carrier into the field of the optical inspection device.

6. An inspection apparatus comprising a base, a movable carrier having a card supporting surface thereon, holders on said carrier for holding a potentiometer card in position on said card supporting surface, means mounting said carrier on said base for movement in a predetermined path whereby said card supporting surface is guided in a predetermined path of movement, a stationary optical inspection device mounted on said base adjacent the path of movement of said card supporting surface for use in inspecting a card on said carrier, a capstan mounted on said base, a strand having its intermediate portion encircling and operatively engaging said capstan, means for connecting the ends of said strand at widely separated points to said carrier, and resilient means associated with said strand for maintaining said strand taut and in operative engagement with said capstan whereby, upon rotation of said capstan, the strand is moved to advance the carrier and thereby move successive portions of the card mounted on said carrier into the field of said optical inspection device.
